TORPEDO LOWERING HOOK

William Y. Bleakley and Willy A. Schillinger,
Tulsa, Okla., assignors, by mesne assignments,
to Zero Hour Bomb Company, Tulsa, Okla., a
corporation of Oklahoma

Application July 14, 1939, Serial No. 284,530

5 Claims. (Cl. 294—83)

This invention relates to torpedo hooks and more particularly to a torpedo hook having improved means for controlling a closure member which, when in closed position, prevents release of a torpedo or bomb secured to the lowering cable by the hook.

In the operation of oil wells it is frequently necessary to lower torpedoes containing a charge of high explosive or a time bomb into the well. The torpedo or bomb is secured to the end of a lowering cable by means of a torpedo hook. It is necessary that accidental release of the bomb or torpedo during lowering into the well be prevented but, at the same time, the hook must be capable of releasing the bomb or torpedo when it reaches the point where it is to be exploded.

Various constructions have been proposed for locking or securing a torpedo to a torpedo hook and permitting the release of the torpedo from the hook when desired. In the present invention we have provided improved means for this purpose. The hook is provided with a sliding, locking or closure member which will positively prevent premature release of the torpedo while it is being lowered into the well and which may be released by a series of jerks of the cable when the torpedo is at the bottom of the well.

Among the many advantages of our construction are its compactness, the absence of projections from its exterior which avoids snagging when lowered into a well and the arrangement of the moving parts so that they all move relatively freely in unobstructed openings. The latter feature is particularly advantageous in that the construction contains no pockets or corners which might receive and hold sand or dirt and thereby interfere with the operation of the device.

Another important feature of the present invention is the provision of a weighted head which causes relative movement between two parts of the apparatus when the torpedo is at the bottom of the well by slackening the cable and actuates the release of the mechanism of the locking member. Heretofore similar devices have been provided with springs for the purpose of causing movement of one of the two movable parts in one direction to assure actuation of the releasing mechanism of the locking device.

In the accompanying drawing we have shown one embodiment of the invention. In this showing:

Fig. 1 is a vertical, longitudinal, sectional view;
Fig. 2 is a front view of the hook;
Fig. 3 is a detailed view of a sliding stem form-

ing a portion of the hook in front elevation; and Fig. 4 is a view showing the hook carrying an explosive shell in lowering position in a well.

The body portion of the hook comprises a pair of side plates 10. A hook member 11 is mounted between the lower ends of the side plates and the hook member is provided with a recess 12 to receive the bail 13 of a torpedo shell 14 when the torpedo shell is to be lowered in a well casing 15 as shown in Fig. 4 of the drawing. A spacer 16 is arranged between the upper ends of the side plates 10 and this spacer is provided with an axial opening 17. A stem 18 extends through this opening, the stem being provided with a shoulder 19 on the portion of the stem arranged within the body which limits its upward movement with respect to the body portion of the hook. The upper end of the stem 18 is mounted to freely swivel on ball bearings 20 carried in a head 21. As shown, the head is made in two sections, the lower portion having an axial opening 22 for the reception of the upper end of the stem 18. At its extreme upper end the stem is threaded as at 23 for the reception of a nut 24 which retains the stem in the head. The upper portion 25 of the head is secured to the lower portion by screw threads and its upper end is provided with an ear having an opening 26 for the reception of a lowering cable 27.

The main portion of the stem which is arranged within the body between the side plates 10 is provided with a longitudinal slot 28. A pawl 29 is pivotally mounted in this slot and a spring 30 is secured to the stem within the slot as at 31 and has its free end in engagement with the pawl normally tending to rotate it in a counter-clockwise direction. Tooth 32 carried on the other end of the pivoted pawl is therefore normally thrust toward the front of the body of the hook by the spring 30.

The hook is provided with a longitudinal slot 33 which receives the lower end of a flat sliding closure member 34. The closure member is mounted between the side plates 10 adjacent the front of the body and slides in a guide-way 45 formed by cross members or pins 36. As shown two or more of these cross members may be arranged in front of the sliding closure member 34 and one of the cross members may be arranged in the rear of the sliding closure member. The pins 36 carry rollers 35 adjacent each end which form a channel substantially equal to the width of the sliding closure member 34 and the sliding closure member is arranged in this channel to prevent lateral displacement of it. A pin 37, 55

projecting from the front of the closure member, is adapted to engage the lower guide 35 to limit the downward movement of the closure member. The sliding closure member has a series of ratchet teeth 38 on its rear edge which cooperate with the tooth 32 of pawl 29 and likewise has a second series of ratchet teeth 29 on its forward edge which cooperate with a spring 40 mounted on a pin 41 extending between the side plates 10. 5 When in operative position the tooth 32 and the spring 40, in engagement with their respective ratchet teeth, prevent downward movement of the sliding closure member 34 but permit upward movement thereof.

10 15 In the operation of the device with the sliding closure member 34 in the raised dotted line position shown in Fig. 1 of the drawing and the hook open, the bail 13 of the torpedo shell is placed in the recess 12 of the hook. The slide is then released to assume its operative position by pressing upon the lower end of the pawl 29 to release the tooth 32 from the ratchet teeth 38 and by pulling the spring 40 outwardly to release it from the teeth 39. The closure member then moves 20 by gravity into slot 33 of the hook and while in that position, it prevents release of the torpedo 14 by the hook. While the torpedo shell is being lowered into the well, the weight of the hook device and the suspended shell rests upon shoulder 25 19 and the slide 18 and head 21 are moved upwardly from the body portion of the hook to their extreme position. When the shell comes to rest on the bottom of the well, it may be released from the hook by slackening the cable 27. The weight 30 35 of the torpedo and hook being no longer supported by the cable, this slackening permits the head 21 to move downwardly of its own weight a distance equal to and limited by the clearance between the body 10 and the lower end of the 40 head 21. This is sufficient to allow tooth 32 of pawl 29 to engage the next lower ratchet tooth 38. By then taking up the slack in the line and moving the stem 18 upwardly until shoulder 19 again engages the spacer 16, pawl 22 lifts the closure slide 34 a distance equal to the distance between two of the ratchet teeth 38. Spring 40 45 immediately engages the next lower tooth 39, the spacing of the teeth 38 and 39 being the same, and holds the slide in elevated position while the 50 cable is again slackened and pawl 29 permitted to engage the next lower tooth. This operation is repeated until the sliding closure member 34 has been moved upwardly in the body 10 sufficiently to permit the release of the bail 13 from the recess 12 in the hook member. Two or three pulls 55 upon the cable 27 are generally sufficient, whereupon another slackening movement of the cable will permit the hook to release itself and the cable 27 and hook may then be withdrawn from the 60 well.

It will be apparent that the device is of simple construction and that it is particularly adapted for use in oil wells because of its compactness and foolproofness. The arrangement of the operating parts within the body 10 and the positioning of these parts in such manner that corners and pockets are eliminated is also particularly advantageous because it prevents mud or dirt from packing in the path of moving parts and thus 65 preventing the operation of such parts.

We claim:

1. Apparatus of the character described comprising a pair of side plates, a hook secured to the lower ends of the side plates, the hook being 70 provided with a slot extending from the top to

the bottom thereof, a spacing member secured to the upper ends of the side plates, the spacing member having an opening formed therein, a stem passing through the opening, a shoulder on the stem to limit its upward movement, a head 5 secured to the stem exteriorly of the side plates, a locking member slidably mounted between the side plates and extending into and partially filling the slot when in lowered position whereby fluid may freely flow from the space between the side plates above the hook through the slot, and means controlled by the relative movement of the side plates and the stem for raising the locking member to an inoperative position.

2. Apparatus of the character described comprising a pair of side plates, a hook secured to the ends of the side plates, the hook being provided with a slot, a spacing member secured to the upper ends of the side plates, the spacing member having an opening formed therein, the space between the side plates being open at the front and back, a stem passing through the opening in the spacing member, a shoulder on the stem to limit its upward movement, a head secured to the stem exteriorly of the side plates, a locking member 20 25 slidably mounted between the side plates and extending into the slot when in lowered position, ratchet teeth formed on the locking member, and a pawl carried by the stem and adapted to engage 30 said teeth.

3. Apparatus of the character described comprising a pair of side plates, a hook secured to the lower ends of the side plates, said hook being provided with a vertically disposed slot extending from the top to the bottom thereof, a spacing member secured between the side plates at their upper ends, the spacing member having an opening therein, a stem passing through said opening, a shoulder on the stem to limit its upward movement, a head secured to the stem above the spacing member, a locking member 35 40 45 slidably mounted between the side plates and extending into and partially filling the slot in the hook when in lowered position whereby fluid may freely flow from the space between the side plates above the hook through said slot, and means controlled by the relative movement of the side plates and stem for raising the locking member to an inoperative position.

4. Apparatus of the character described comprising a pair of side plates, a hook secured to the lower ends of the side plates, the hook being provided with a slot, a spacing member secured to the upper ends of the side plates, said spacing member having an opening formed therein, the space between the side plates being open at the front and back, a stem passing through the opening in the spacing member, a shoulder on the stem to limit its upward movement, a head comprising a lower section having an axial opening 55 60 65 for the reception of the stem and an upper section secured thereto, the head being free to swivel on the stem, a locking member slidably mounted between the side plates and extending into the slot when in lowered position, and means controlled by the relative movement of the side plates and the stem for raising the locking member to an inoperative position.

5. Apparatus of the character described comprising a pair of side plates, a hook secured to the lower ends of the side plates, the hook being provided with a slot extending from the top to the bottom thereof, a spacing member secured to the upper ends of the side plates, the space between the plates intermediate the hook and the spac- 70 75

ing member being open, the spacing member having an opening therein, a stem passing through the opening, means for limiting the upward movement of the stem, a head secured to the stem exteriorly of the side plates, a locking member slidably mounted between the plates and extending into and partially filling the slot when in

a lowered position, and means controlled by the relative movement of the side plates and the stem for raising the locking member to an inoperative position.
